HEAT CONSERVATION MEANS FOR
DOMESTIC HOT-WATER SYSTEMS

Frank G. Campbell, Arlington County, Va.

Application May 5, 1945, Serial No. 592,088

3 Claims. (Cl. 237—19)

1

The object of the invention is to provide such connections between the domestic heating pipes of a house heating system and the hot water service supply pipes of the building as to radically reduce the cost of supplying hot water to the kitchen sinks, basins, etc., of the building.

In the accompanying drawing, Fig. 1 is a diagrammatic view illustrating one layout of piping which may be employed, Fig. 2 is a sectional view illustrating one of the water heating chambers hereinafter described, and Fig. 3 is a view partly in elevation and partly in section showing a radiator wherein one section is used as a compartment through which water flows on its way from the domestic hot water heater to a hot water faucet of a basin, sink, or the like. In the diagrammatic view Fig. 1 the basement floor of a building is indicated at 5, first floor at 6, and the second floor at 7.

A kitchen sink 8 is indicated upon the first floor. A conventional wash basin 9 is indicated upon the second floor. The incoming cold water supply line 10 supplies cold water through the branches 11 and 12 to the cold water faucets 13 and 14 of the sink and basin, respectively. A branch 15 from the line 10 constitutes the cold water supply line to a conventional automatic, domestic, hot water heater 16. This may be either electric or gas. These conventional automatic domestic hot water heaters are now commonly employed. They are usually located in the basement, or other low point in the domestic water supply and they comprise automatic means for turning on the heating medium, either gas or electricity, whenever by the opening of a hot water faucet hot water is withdrawn from the heater. A cold water supply line leads to the heater and the domestic hot water service supply line leads from the heater to the hot water faucets of the various fixtures to be serviced, such as sinks, basins, etc., usually upon the upper floors of the building. The domestic hot water service line leading from the heater 16 is indicated at 17 and the hot water faucets for the sink and basin respectively are indicated at 18 and 19. Located in the domestic hot water service line between the heater 16 and the hot water faucet 18 of sink 8 is a chamber 20, and located between heater 16 and the hot water faucet 19 of the basin 9 is a chamber 21. The hot water service line 17 enters the chamber 20 at the bottom of said chamber and leaves from the point near the top of said chamber as indicated by the branch 17a. A branch hot water service line 17b enters the chamber 21 near the bottom and leaves

2

near the top as indicated by the branch 17c. Thus whenever a hot water faucet is opened either at sink 8 or basin 9, a flow of water is set up through the heater 16 and through either chambers 20 or 21 as the case may be. As stated the domestic hot water heater 16 may be either gas or electric. In an electric domestic water heater of this type the electricity is turned on automatically whenever the water temperature in the heater drops below a set point. In many domestic gas water heaters of this type the gas is automatically turned on whenever the temperature of the water in the heater falls below a set point. In the flash type of domestic gas water heater the gas is turned on by the reduction of water pressure occasioned by the opening of a hot water faucet. In every case the withdrawal of hot water from the heater 16 through hot water service line 17 calls for the expenditure of heat, either gas or electric, to replace the hot water so withdrawn. Located in the rooms occupied by the sink and basin 9 respectively are the room or space heating elements such as radiators 22 and 23. The heating medium, which may be either steam or hot water is supplied to these radiators through the house heating fluid supply pipe 24, said supply pipe leading from a conventional house heating boiler 25 in the basement. This house heating fluid supply pipe passes through the chambers 20 and 21, said chambers being located upon the floors occupied by the sink and basin respectively.

While I have shown a building having only two floors above the basement it is to be understood that the described arrangement may be carried out in buildings of any number of floors. As this description proceeds it will be seen that the utility of the invention increases with the height of the building or the number of its floors. The purpose of providing the chambers 20 and 21 is to provide a reservoir of hot water in relatively close proximity to the hot water faucets upon each floor. This is accomplished by carrying the house heating pipe 24 of the radiators through the chambers 20 and 21, as described. The contact of the body of water lying in the chambers 20 and 21 with the pipe 24 passing therethrough results in heating the domestic hot water from the house heating boiler, and maintaining a reservoir of domestic hot water close to each of the water faucets.

This results in very great savings of both fuel and water for the following reasons. Under present day practice and lacking the heat exchangers 20 and 21 of this invention a person,

say at basin 9, desiring merely enough hot water to wash his hands turns on the hot water faucet and lets the water run long enough for water from the domestic hot water heater 16 to travel all the way from the basement to the basin 9. By providing the chamber 21 containing a body of water the temperature of which is boosted by pipe 24, such person would be able, in most cases, to get enough hot water to wash his hands from the adjacent chamber 21. He would not have to wait for hot water to travel all the way from heater 16 to faucet 19. Thus the described arrangement results in saving, not only what ever water is wasted every time the pipe is emptied back to the heater, but also in saving the heat at heater 16 required to bring the fresh supply of incoming cold water up to the temperature formerly held by the water it replaces. It should be borne in mind that when a faucet, 19 for example, is opened to secure only a small amount of hot water, there is occasioned a considerable loss from two sources, namely the water that is wasted down the drain from pipes 17, 17c during the time it takes the hot water to travel from heater 16 to faucet 19 and the waste of heat units (gas or electric) which takes place after faucet 19 is closed and the pipe full of hot water between faucet 19 and heater 16 gradually cools down and possibly becomes altogether cold before some one again opens faucet 19.

The monetary loss occasioned by the necessity of permitting a considerable amount of water to escape down the drain pipe every time a hot water faucet is opened is a considerable loss at even a single household. When multiplied by the millions of homes throughout the nation it will be seen that the loss nationally is a very great one indeed. It is to be understood that the invention is not limited to the particular arrangement shown. Fig. 1 is intended to be merely a diagrammatic layout wherein the spaces A and B may be the partition walls of a building. However, the chambers 20 and 21 may be located beneath the floors or in any other suitable place where the steam and water pipes of a building are ordinarily placed. However, one advantage of arranging the chamber 21 vertically as shown, and of having the hot water line enter at the bottom and leave at the top, is that these chambers will drain completely, along with the remainder of the piping, when the system has to be drained in winter to prevent freezing.

It is to be observed that the advantage of the invention may be had at a very small cost. It amounts to no more than making an enlargement in the domestic hot water service pipes adjacent each hot water faucet and having such enlargement embrace a part of the house heating pipe 24. The latter has to be put in place any way, and the hot water service lines have to be put in place any way. Therefore, the increased cost would reside merely in the chambers 21 and these would be preferably placed on the market for sale in plumbers supply houses and comprise chamber 21 having a short section of the pipe 24 welded in place therein as at x, said short sections being provided with unions 30 by which chamber 21 could be easily and quickly connected into the line 24. It is to be observed that the supply to the hot water faucets upon the several floors is through a pipe that is wholly independent of the supply to the associated cold water faucets so that tempered water may be had at any basin by simultaneously discharging

hot and cold water from said associated hot and cold water faucets.

In Fig. 3 I have indicated that a heating radiator may be employed to heat a limited body of water adjacent a hot water faucet. Here the radiator has its first section 35 connected to its third section 36 by elongated nipples 37. A water storing and heating chamber 20a corresponding in general shape and size with the remaining 10 radiator sections lies between and is heated by sections 35 and 36. The hot water pipe supply line for a hot water faucet (corresponding to service line 17) enters chamber 20a at 17e and leaves at 17f, it being understood that chamber 20a then performs the function performed by chambers 20 and 21, namely it provides, adjacent a hot water faucet, a limited supply of hot water which reaches a wash basin or sink far ahead of water flowing from the water heater in the basement, when said faucet is opened. While this limited supply of water is heated by the radiator it is separate and distinct from the body of water or steam which serves to heat the radiator.

It is within the scope of the invention to associate with each of the reservoirs 20 and 21 independent heating means, such as an electric heating coil 20x, 20y. This renders it possible to heat each reservoir independently, and independent of pipe 24. Thus the advantages of the 30 invention may be had in summer when the boiler 25 is not in use.

The invention includes within its purview whatever changes fairly come within either the terms or the spirit of the appended claims.

Having described my invention what I claim is:

1. In a combined house heating and domestic hot water supply system for a building having a basement and a plurality of floors above said basement, of a house heating boiler in the basement, a space heating radiator located upon each of the said floors of the building, a heating fluid supply line leading from the boiler to all of said radiators, an automatic hot water heater located in the basement of a type wherein the cold water supply line of the building delivers an additional supply of water into the heater whenever by the opening of a hot water faucet, hot water is withdrawn from said heater and wherein the heater is set in operation to heat additional water upon 40 the withdrawal of a predetermined amount of hot water therefrom, a domestic hot water service line leading from the hot water heater to a plurality of hot water faucets, one of said faucets being located upon each of the floors, an auxiliary hot water storage chamber included in and forming part of the hot water service line adjacent each of the hot water faucets, said chambers having heat interchange relation with the heating fluid supply line of the radiator, a cold water faucet associated with each hot water 45 faucet and a cold water supply line leading to all of the cold water faucets, whereby when any hot water faucet is opened hot water is delivered thereto from its associated auxiliary hot water 50 storage chamber and without interference with a simultaneous discharge of cold water from the associated cold water faucet.

2. In a combined house heating and domestic hot water supply system for a building having a basement and a plurality of floors above said basement, of a house heating boiler in the basement, a space heating radiator located upon each of the said floors of the building, a heating fluid supply line leading from the boiler to all of said 70 radiators, an automatic hot water heater located

in the basement of a type wherein the cold water supply line of the building delivers an additional supply of water into the heater whenever by the opening of a hot water faucet hot water is withdrawn from said heater and wherein the heater is set in operation to heat additional water upon the withdrawal of a predetermined amount of hot water therefrom, a domestic hot water service line leading from the hot water heater to a plurality of hot water faucets, one of said faucets being located upon each of the floors, an auxiliary hot water storage chamber included in and forming part of the hot water service line adjacent each of the hot water faucets, said chambers having heat interchange relation with the heating fluid supply line of the radiators.

3. A structure as recited in claim 2 in combination with a heating means associated with each of the auxiliary hot water storage chambers, said

heating means being independent of and in addition to the heating fluid supply line of the radiator.
